United States Patent Office

Des. 218,188

Patented July 28, 1970

218,188

FRAME FOR A CLOCK OR THE LIKE

Harry Bergman, Glencoe, Ill., assignor to Butler Specialty Company, Chicago, Ill., a corporation of Delaware

Filed May 29, 1969, Ser. No. 17,479

Term of patent 3½ years

Int. Cl. D10—01

U.S. Cl. D42—7

FIG. 1

FIG. 2

FIG. 1 is a front elevational view of a frame for a clock or the like showing my new design; and

FIG. 2 is a side elevational view.

I claim:

The ornamental design for a frame for a clock or the like, as shown.
